US0D1033649S

(12) **United States Design Patent** (10) **Patent No.:** **US D1,033,649 S**
(45) **Date of Patent:** **** Jul. 2, 2024**

(54) **VISION FOCUS DEVICE**

(71) Applicant: **David Han**, Yorktown, VA (US)

(72) Inventor: **David Han**, Yorktown, VA (US)

(**) Term: **15 Years**

(21) Appl. No.: **29/864,185**

(22) Filed: **May 12, 2022**

(51) **LOC (14) Cl.** **24-02**

(52) **U.S. Cl.**

USPC **D24/172**; D2/866; D16/300

(58) **Field of Classification Search**

(57) **CLAIM**

The ornamental design for a vision focus device, as shown and described.

DESCRIPTION

FIG. 1 is a front elevation view of a first embodiment of a vision focus device, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front perspective view thereof as worn by a user;

FIG. 8 is a front elevation view of a second embodiment of the vision focus device;

FIG. 9 is a rear elevation view thereof;

FIG. 10 is a left side elevation view thereof;

FIG. 11 is a right side elevation view thereof;

FIG. 12 is a top plan view thereof;

FIG. 13 is a bottom plan view thereof; and,

FIG. 14 is a front perspective view thereof.

(Continued)

The broken lines depict environment and form no part of the claimed design.

1 Claim, 14 Drawing Sheets
